UNITED STATES PATENT OFFICE.

STARRATT D. NICHOLS, OF BUFFALO, NEW YORK.

DESIGN FOR A CUP AND SAUCER.

Application filed June 22, 1921. Serial No. 479,667. Term of patent 7 years.

To all whom it may concern:

Be it known that I, STARRATT D. NICHOLS, and saucer, showing my new design. a citizen of the United States, residing at Buffalo, in the county of Erie and State of New York, have invented a new, original, and ornamental Design for a Cup and Saucer, of which the following is a specification, reference being had to the accompanying drawings, forming part thereof.

The figure is a perspective view of a cup and saucer, showing my new design.

I claim:

The ornamental design for a cup and saucer, substantially as shown.

STARRATT D. NICHOLS.
